INSULATOR TIE

Edward C. Carlson, Chicago, Ill., assignor to
Harold S. Sines, Chicago, Ill.

Application February 17, 1948, Serial No. 8,851

2 Claims. (Cl. 174—139)

1

My invention contemplates as its object and provides an improved tie which cooperates with a line conductor and an insulator therefor effectively to secure the conductor in appropriate non-chafing and substantially non-vibratory relation to the insulator while at the same time maintaining in electrical connection with the conductor an appurtenant device which by virtue of said tie is physically supported quite independently of the conductor by the insulator, to the end that the weight of such appurtenant device shall not cause conductor disruption and/or radio interference and/or other impairments of power transmission service.

An appurtenant device of the class contemplated by the foregoing paragraph may be a capacitor, a lightning arrester, a hot line clamp, a take-off connector or any other instrumentality of significant mass which requires physical support as well as electrical connection with the conductor. Such appurtenant devices, as heretofore associated with wire-tied line conductors, have been responsible for a large number and variety of service impairments such as conductor fatigue, conductor abrasion, loosening of the tie wires, burning of conductor or tie wires, etc., brought about by mechanical strains imposed upon the conductors by such devices.

Other objects, features and advantages of my invention will appear from the detailed description to follow which makes reference to the accompanying two sheets of drawings wherein

Figure 1 is a top plan view depicting a preferred form of my improved tie and other instrumentalities with which it cooperates in service;

Figure 2 is a side elevational view of the same;

Figure 3 is an isolated plan view of the "wish-bone" element of the tie as such element appears before installation;

Figure 4 is a sectional view which may be regarded as taken in the horizontal plane of the line 4—4 of Figure 2 and looking in the direction indicated by the arrows;

Figure 5 is a top plan view of a modified form of my improved tie and other instrumentalities with which it cooperates in service;

Figure 6 is a side elevational view of the same;

Figure 7 is a sectional view which may be regarded as taken in the horizontal plane of the line 7—7 of Figure 6 and looking in the direction indicated by the arrows; and

Figure 8 is a view largely in side elevation but partly in section which may be regarded as taken in the vertical plane of the line 8—8 of

2

Figure 5 and looking in the direction indicated by the arrows.

Similar characters of reference indicate similar parts throughout the several views.

5 Referring first to Figures 1 to 4, both inclusive, reference character A denotes a conventional insulator, of porcelain or other dielectric, which for the purposes of the present specification may be regarded as representative of the various types of insulators with which the tie of my present invention may be associated. The particular insulator chosen for purposes of illustration comprises a knob-like circular top B in the upper surface of which is formed a diametrically extending groove C. The insulator will be so mounted on a cross arm or other support that groove C extends in the direction of the conductor with which the insulator is associated. Encircling the insulator immediately beneath 10 the knob-like top B is the annular groove D. In transverse section, the wall of groove D preferably is arcuate and the wall of groove C approximately so. At E is indicated the line conductor with which insulator A is associated.

15 At 10 in Figure 2 is indicated an electricity conducting tension member which may be presumed to carry in suspension at its lower end and to be electrically connected with an appurtenant device (not shown) such as, for example, a capacitor, lightning arrester or the like. As will presently appear, my improved tie, which 20 comprises an electricity-conducting supporting arm 11 to which I shall make further reference, at all times keeps the tension member 10, and the appurtenant device suspended thereby, in electrical connection with line conductor E while 25 shielding such line conductor from all strain imposed upon the tie by the weights of such electricity-conducting tension member 10 and such appurtenant device. The upper end of member 10 conveniently is attached to supporting arm 11 by a conventional or other connector 12 which desirably is of the nut actuated clamp type.

30 40 Supporting arm 11 constitutes one end of an integral hard-drawn preformed wire which also comprises an eye loop 13, a helix 14 to embrace and for some distance co-extend with line conductor E, and a reach portion 15 which joins eye loop 13 and helix 14.

45 The integral hard-drawn preformed wire, comprising the portions 12, 13, 14 and 15 as aforesaid, may be regarded as the first of three essential and initially separate constituents of the 50 subject tie. The second of those constituents

is another integral hard-drawn pre-formed wire presenting an eye loop 16, a helix 17, and a reach portion 18 joining eye loop 16 and helix 17. The third of such constituents is a so-called "wishbone" consisting of a piece of wire having its ends twisted together at 19 and conformed between its twisted ends to provide the generally U-shaped portion 20 having the eyes 21-21 presented by the extremities of its generally parallel portions 22-22.

In applying the tie comprising the constituents just described, a lineman proceeds as follows: The helices 14 and 17 of the two hard-drawn pre-formed wires are spiraled upon the line conductor E (or any armor rods or the like which may be on the conductor) firmly to engage the latter on opposite sides of the insulator A, the two reach portions 15 and 18 of such wires are brought into the insulator top groove C, and the two eye loops 13 and 16 are caused to lie in the annular groove D of the insulator; the two eye loops lying in groove D adjacent diametrically opposite portions of the insulator and occupying substantially vertical planes. Then the generally parallel portions 22-22 of the "wishbone" are threaded through eye loops 13 and 16 and the extremities of the portions 22-22 of the "wishbone" are twisted together at 23 (conveniently with a twisting bar extended through eyes 21-21) to cause the applied "wishbone" tightly to embrace the upper portion of the insulator A and firmly hold the eye loops 13 and 16 vertically disposed in the insulator groove D, and to provide a strong outwardly extending arm. Then, because of the hard-drawn preformed character of the wires which comprise such eye loops 13 and 14, the line conductor E stands attached to the insulator A while being held out of contact with it, with vibration of the line conductor E in the region of the insulator A being effectively damped to a minimum by the helices 14 and 17. Moreover, and very important, when the electricity-conducting tension member 10 subsequently is attached to supporting arm 11, all of the weight of the tension member 10 and any appurtenant device suspended by it is thrown upon the insulator through loop eye 13, and not any strain resultant from the carrying of such weight is thrown upon the line conductor. If desired, the loop eye 16 may be provided with a supporting arm similar to and for the same purpose as the supporting arm 11 which emanates from loop eye 13.

That modified form of my multiple purpose tie which is depicted in Figures 5 to 8, both inclusive, comprises two hard-drawn preformed wire members, a "wishbone" member and a flexible conducting member, interposed between the line conductor and the "wishbone" element when the latter is installed. In this modification each hard-drawn preformed wire member consists of a helix 30, a terminal loop eye 31 and a reach portion 32 integrally joining portions 30 and 31. In other words, each of these members is substantially identical with the hard-drawn preformed wire member of Figures 1 to 4 which comprises loop eye 16, helix 17 and reach portion 18. The "wishbone" element of Figures 5 to 8 may be substantially identical with the corresponding element of the preceding figures and bears the same reference numerals. The flexible conducting member desirably is in the form of a metallic tape or ribbon 33 applied directly to the conductor or any armor rods or the like which may exist on the conductor.

In effecting the tie of Figures 5 to 8, a lineman

proceeds as follows: The intermediate portion of metallic tape or ribbon 33 is spiraled upon that portion of line conductor E which is to overlie insulator A, the tape or ribbon being left with 5 liberal end portions extending away from conductor E. The helices 30-30 are spiraled upon conductor E firmly to engage the latter on opposite sides of insulator A. The two reach portions 32-32 are brought into the insulator top 10 groove C, and the two eye loops 31-31 are caused to lie in annular groove D of the insulator adjacent diametrically opposite portions of the insulator. Then the portions 22-22 of the "wishbone" element are threaded through the eye loops 15 31-31. Then the extremities of the tape or ribbon 33 are spiraled around the portions 22-22 of the "wishbone" element, in regions lying between the eye loops 31-31 and the extremities of such portions 22-22. Then the extremities of 20 such portions 22-22 are twisted together as at 23 so as to provide an outwardly extending arm and to cause the applied "wishbone" tightly to embrace the upper portion of insulator A, tightly clamp and hold the ends of tape or ribbon between portions 22-22 and the insulator, and firmly hold the eye loops 31-31 vertically disposed in insulator groove D.

In this instance, the conducting tension member 10 is attached by a clamp type connector 12 30 to the arm provided by the ends of the "wishbone" element which have been twisted together at 23. By virtue of this, and the assembly of parts described in the preceding paragraph, all 35 weight of the tension member 10, and any appurtenant device suspended by it, is thrown upon insulator A through the "wishbone" element and the loop eyes 31-31, not any strain resultant from the carrying of such weight being thrown upon line conductor E, while a dependable electrical connection between such appurtenant device and the line conductor is afforded through conducting tension member 10, connector 12, the "wishbone" element and the flexible tape or ribbon 33 and armor rods or the like if any such happen to be on the conductor.

Having thus illustrated and described my invention, what I claim as new and desire to secure by Letters Patent of the United States is:

50 1. In combination, an insulator having an exterior annular groove near one end, a line conductor extending across the end of the insulator, a binding element lying in the groove and embracing the insulator, ties connecting the binding element and regions of the line conductor 55 at opposite sides of the insulator, and an electricity-conducting supporting member connected directly to the binding element at the insulator independently of the line conductor, one of said ties having a loop extending about the binding element, and the electricity-conducting supporting member being integral with the loop.

60 2. For use with an insulator having an exterior annular groove near one end, a line conductor extending across the end of the insulator and a binding element embracing the insulator in said groove, the combination comprising ties 65 for connecting the binding element and regions of the line conductor at opposite sides of the insulator, and an electricity-conducting supporting member for connection directly to the binding element at the insulator independently of the line conductor, at least one of said ties having a loop therein for encompassing the binding element, and the electricity-conducting supporting

member being integral with the loop on said one of the ties.

EDWARD C. CARLSON.
